SAFETY AND CHANGE-OVER MECHANISM FOR MOVING-PICTURE-PROJECTING MACHINES

Application filed December 27, 1927. Serial No. 242,609.

This invention relates to moving picture projecting machines, and more especially to apparatus for facilitating the change over from one machine to another and for operating automatically to cut off the light from the film in the event of accident, as for example, the breaking of the film or the stopping of its feeding movement for any reason.

When the roll of film in one projecting machine is about to run out, it is necessary to start up or "bring in" another machine and to produce an instantaneous change over from one machine to another in order to avoid any break in the picture. Before the second machine can be brought into operation it is necessary to start it up and "spot the light" to be sure that it is working properly. Usually the change over then is made by the two machine operators working together, one cutting off his machine at practically the same instant that the other operator cuts in the second machine.

In my prior application Serial No. 730,381 I have disclosed a mechanism in which the safety apparatus is used in producing a change over, the organization being such that a single operator can make the change over unaided. This arrangement has proved very satisfactory and represents a substantial advance in this art. The present invention aims further to improve and perfect apparatus of this character with a view to simplifying the apparatus, reducing the expense of manufacture, facilitating the operation of the apparatus to effect the change over, and devising a sturdy and more substantial construction. It is also an object of the invention to devise an apparatus which will perform both the functions of preventing ignition of the film in the case of accident, and also enabling a single operator to perform the operations of cutting out one machine and simultaneously cutting in another.

The nature of the invention will be readily understood from the following description when read in connection with the accompanying drawings, and the novel features will be particularly pointed out in the appended claims.

Referring now to the drawings,

Figure 1 is a diagrammatic view showing parts of a moving picture projector equipped with apparatus embodying this invention;

Fig. 2 is a perspective view of the dowser and the operating means therefor;

Fig. 3 is a rear elevation of the parts shown in Fig. 2;

Fig. 4 is a front elevation of the dowser and adjacent parts;

Fig. 5 is a view, partly in side elevation and partly in cross-section, showing the connections between the dowser and the switches associated therewith; and

Fig. 6 is a diagrammatic view showing the electrical connections between two machines.

Referring first to Fig. 1, the apparatus there shown comprises a lamp house or casing 2 of any suitable construction provided with the usual cone 3 projecting from the front thereof. The beam of light transmitted through the cone strikes the film 4 which is being fed intermittently by the usual mechanism past the aperture in the machine casing 5. This film passes over the intermittently rotating sprocket feed roll 6 around the loop setter roll 7, thence over another feed roll 8 and into the lower magazine 9 where it is wound up on the takeup reel, all of this mechanism being substantially like that of the usual moving picture projector.

This machine is equipped with a dowser or shutter 10 which is releasably held in its open position by an electro-magnetic mechanism which includes the electro-magnets 12, the arrangement being such, as will be described more fully hereinafter, that upon the energizing of the magnets the dowser is released and drops automatically into position to shut off the light from the film 4. The circuit in which this electro-magnetic mechanism is connected includes two switches indicated diagrammatically at 13 and 14, Fig.

1. The upper switch 13 is arranged to be operated automatically by the loop setter in case the loop is lost for any reason, and for this purpose the switch is provided with an operating lever 15 which bears against a knob 16 that is moved automatically on the loss of the loop, thus resulting in closing the 100

switch 13. The lower switch 14 is arranged to be closed automatically upon the breaking of the film, the operating mechanism for the switch including a lever 17 carrying a roll 18 which bears against the film. All of this switch mechanism and the means for operating it automatically is like that shown and described in my pending application Serial No. 66,746 to which reference should be made for a complete explanation of the construction and operation of the mechanism. For present purposes it is sufficient to point out that if the film is broken, or its feeding movement is interrupted, one or the other of the switches 13 or 14 will be closed thus energizing the electro-magnetic mechanism 12, and automatically releasing the dowser. This cuts off the light from the film and prevents ignition of the film. While the switching mechanism shown in my earlier application has been illustrated here for purposes of explanation, it will be understood that other automatically operated switches can be used to close the circuit which releases the dowser. The present invention involves improvements in the mechanism for operating the dowser and also an improved arrangement whereby the automatic dowser may also be used in effecting the change over. Referring more especially to Figs. 2 to 5, the dowser 10 preferably comprises two plates spaced apart but secured to each other and mounted on an arm 20 which is cast integral with a hub 21. This hub is fastened to a bushing or sleeve 26 through which a shaft 22 extends, the bushing being mounted to rock in a bearing 23 which may conveniently be cast integral with a part 24 of the casing for the electro-magnetic mechanism. A foot plate 25 is secured to this casing and is adapted to be fastened to the cone 3 projecting from the lamp house. This mounting of the dowser permits it to swing from the open position shown in Figs. 2, 3 and 4 into a closed position directly in front of the cone 3. The dowser hub 21 also carries a handle 27 by means of which the dowser can be operated manually. Secured fast to the bushing 26 is a short sleeve 28, Fig. 5, having an arm 29 projecting forward therefrom, and a hardened latch 30 is secured to the bottom of this arm. Normally the outer end of this plate is engaged by another hardened plate 31, Fig. 3, which is secured to an armature 32 pivoted at 33 and having a part extending upwardly within the field of the electro-magnets 12. A spring 34 of phosphor bronze, or other non-magnetic material, is interposed between the armature 32 and the magnets 12 and tends to hold the armature in its latching position, as shown in Fig. 3. For the purpose of limiting the outward movement of the armature under the influence of the spring 34, a stop 35, Figs. 2 and 3, is provided. The armature

also carries an L-shaped piece 36 at its lower end which serves as a stop for the latch 30 to limit the opening movement of the dowser, this movement being also limited by a stop pin 37, Fig. 4.

The apparatus is adapted to operate on either alternating or direct current, and the circuit connections will be readily understood from an inspection of Fig. 6 which shows the wiring diagram for two machines. If direct current is used it is preferable to include resistances in the supply circuit, the resistance boxes being indicated at 40—40. It will be observed that each machine is equipped with an automatic dowser under the control of the electro-magnetic mechanism and that each machine also is equipped with switches 13 and 14 under the control of the film for closing the circuit through the electro-magnets of its own machine to release the dowser in the event of an accident in the feeding of the film. When either machine is in operation the dowser for that machine is held in its open position, as shown in Figs. 2, 3 and 4, by the armature 32, the hardened latch 30 being held between the stop 36 and the hardened member 31 of the armature, as clearly shown in Fig. 3. As soon as the electro-magnets 12 are energized, as, for example, by the closing of one of the switches 12 or 13, the armature is withdrawn, thus releasing the latch 30 and permitting the dowser to drop by gravity into its closed position and thus shutting off the light from the film. When the trouble has been remedied the dowser may be again moved into its open position by operating the handle 27, and it will be held in this position by the engagement of the armature with the latch 30.

In order yieldingly to arrest the movement of the dowser, the latch 30 is provided with an upwardly extending curved blade 41, Figs. 3 and 5, the end of which is adapted to slide into the space between two closely adjacent stationary plates 42, Fig. 5, and be gripped slightly. This prevents the stopping of the movement of the dowser with a severe shock. One edge of the dowser also carries a lug 43, Fig. 2, which may strike the side of the cone 3 and thus act more directly as a stop.

For the purpose of enabling an operator to produce the change over, an electric switch 45 is associated with each dowser, this switch being adapted to close a circuit through the electro-magnetic mechanism of the other machine, provision being made for operating the switch substantially simultaneously with the opening movement of the dowser. As best shown in Fig. 3, the switch 45 comprises upper and lower spring contacts 46 and 47, respectively, insulated from each other and projecting forward over the path of movement of an insulating pin 48 which is carried by

an arm 49 projecting from a sleeve 50 secured fast on the shaft 22. A spring 51, Figs. 3 and 5, coiled about the shaft 22 tends to rotate this shaft in a counter-clockwise direction, as shown in Fig. 3, to hold an arm 52 projecting from the sleeve 50 against a stop 53. At its forward end the shaft 22 has a disk 55 secured thereto and provided with a notch 56. It will be seen from an inspection of Fig. 5 that the handle 27 is offset so that its axis lies directly over the edge of the disk 55. A plunger 57 is mounted to slide axially in this handle. Normally this plunger is held in an upward or retracted position by a coiled spring 58, and a thumb piece 59 is secured to the end of the plunger 57 and projects beyond the end of the handle 28. By pressing inwardly on the thumb piece 59 the end of the plunger 57 can, at a certain position, be entered in the notch 56 and thus connect the shaft 22 operatively with the dowser and handle. That is, the shaft, handle and dowser will move in unison so long as the plunger is held in the notch 56. It will be seen from an inspection of Fig. 3 that if the shaft 22 is rotated in a clockwise direction, the insulating pin 48 will move the lower contact 47 upward, thus closing the switch 45. Assuming that this movement has taken place, if the thumb piece 59 is now released so as to disconnect the shaft 22 from the dowser, the spring 51 will immediately return the arm 49, pin 48, and stop arm 52, to the positions in which they are shown in Fig. 3 where the switch 45 will be open.

In producing a change over, the machine to be "brought in" is started up, the light is "spotted," and the dowser 10 of this machine 40 then will be closed. At this time the other machine, of course, is running. When the operator is ready to cut in the idle machine, he grasps the handle 27 of the dowser for that machine, presses down on the thumb piece 59 to engage the plunger 57 in the notch 56, and then, while holding the plunger in this position, swings the dowser into its fully open position with the handle striking against the stop 37. The dowser is immediately 50 latched in this position by the armature, and the operator releases the handle. This movement of the handle, however, has closed the switch 45, as above described, thus energizing the electro-magnets 12 of the other machine and automatically releasing the dowser of that machine. This cuts out the machine which has been working. The machine which has been idle has been brought in by the opening movement of its dowser as just described. As soon as the thumb piece 59 is released, the switch 45 will immediately be opened again, as above described.

The circuit connections for producing these operations will be clear from an inspection of Fig. 6. It will also be observed that the

change over from either machine to the other can be made in the manner above described.

Figs. 2 and 5 show the machine equipped with two switches like the switch 45, and such an arrangement is desirable in case three machines are used. The electrical connections between three such machines to enable the change over from any one of the three to another will be understood by those skilled in this art from the disclosure already made.

A removable casing member 60, Figs. 3 and 4, is provided to cooperate with the casing part 24 in enclosing the switch 45, the electro-magnets, and the immediately associated parts, this casing being held in its closed position by two screws, one of which is shown at 61 in Fig. 3.

It will now be appreciated that this invention provides a very simple mechanism for producing a change over from one machine to another. The fact that this mechanism utilizes the dowser which forms a part of the safety mechanism of the machine is an important practical advantage. The apparatus can be manufactured and installed economically, and is very easy to operate since the same motion necessary to move the dowser to its open position also operates the switch which controls the dowser of the other machine. An improved dowser operating mechanism has also been provided which is very sturdy and substantial in construction and is extremely reliable.

While I have herein shown and described a preferred embodiment of my invention, it will be understood that the invention may be embodied in other forms without departing from the spirit or scope thereof.

Having thus described my invention, what I desire to claim as new is:

1. In a mechanism for use with moving picture projecting machines, the combination of a dowser, a support on which said dowser is mounted for movement into an open or closed position, mechanism for normally holding said dowser in its open position and including electro-magnetic means for releasing the dowser, said dowser being adapted to be moved manually into its open position, an electric switch, and operating means for said switch arranged to be connected to said dowser to be operated therewith or to be disconnected therefrom at will.

2. In a mechanism for use with moving picture projecting machines, the combination of a dowser, a support on which said dowser is mounted for movement into an open or closed position, mechanism for normally holding said dowser in its open position and including electro-magnetic means for releasing the dowser, a handle connected with said dowser to operate it manually, an electric switch associated with the dowser, and operating means for said switch arranged to

be operatively connected with said handle or disconnected therefrom as desired.

3. In a mechanism for use with moving picture projecting machines, the combination of a dowser, a support on which said dowser is mounted for movement into an open or closed position, mechanism for normally holding said dowser in its open position and including electro-magnetic means for releasing the dowser, an electric switch, a handle for operating said dowser, operating means for said switch, and means carried by said handle and operable by the hand which grasps the handle for operatively connecting said operating means with said handle.

4. In a mechanism for use with moving picture projecting machines, the combination of a dowser, a support on which said dowser is mounted for movement into an open or closed position, mechanism for normally holding said dowser in its open position and including electro-magnetic means for releasing the dowser, an electric switch, a pivoted handle for operating said dowser, operating means for said switch including a part movable about an axis, and means carried by said handle and operable by the hand which grasps the handle for operatively connecting said handle with said part, whereby said handle may be utilized to operate said switch.

5. In a mechanism for use with moving picture projecting machines, the combination of a dowser, a support on which said dowser is mounted for movement into an open or closed position, mechanism for normally holding said dowser in its open position and including electro-magnetic means for releasing the dowser, an electric switch, a pivoted handle for operating said dowser, operating means for said switch including a shaft about the axis of which said handle pivots, and means carried by said handle and operable by the hand which grasps the handle for operatively connecting said shaft with said handle.

6. In a mechanism for use with moving picture projecting machines, the combination of a dowser, a support on which said dowser is mounted for movement into an open or closed position, a bushing mounted to rock in said support, said dowser being fastened to said bushing, a handle secured to said bushing for operating the dowser, means for releasably holding said dowser in its open position including a latch and electro-magnetic mechanism for releasing the latch, a shaft extending through said bushing and mounted to rock therein, an electric switch, means arranged to be moved by said shaft for operating said switch, and means carried by said handle for releasably connecting said shaft with said handle.

7. In a mechanism for use with moving picture projecting machines, the combination of a dowser, a support on which said dowser

is mounted for movement into an open or closed position, a bushing mounted to rock in said support, a handle secured on said bushing for operating said dowser, means for releasably holding said dowser in its open position including a latch associated with said bushing and electro-magnetic mechanism for releasing the latch, a shaft extending through said bushing and mounted to rock therein, an electric switch, means arranged to be moved by said shaft for operating said switch, a spring tending to turn said shaft, and means carried by said handle and operable by the hand which grasps the handle for releasably connecting said shaft with said handle.
